FOLDING STOOL SUPPORTING STRUCTURE

Ralph B. Long, Flint, Mich.

Application December 18, 1946, Serial No. 716,900

1 Claim. (Cl. 155—136)

1

This invention relates to an improvement in a folding stool, and specifically contemplates providing a supporting frame which may be easily and quickly folded into a comparatively small, compact unit.

Although there are numerous varieties of folding stools in existence, the improvement in the supporting structure of the folding type stool proposed in this invention will substantially reduce both the time and expense required in manufacturing the said supporting structure for folding stools of a type presently in use. It is desirable to provide a folding stool with a supporting structure which will occupy a minimum of space when collapsed yet which will safely support a reasonably heavy adult.

Accordingly, a major object of this invention is to provide a supporting structure for a folding stool which may be more readily manufactured than similar supporting structures presently in use.

A further object of this invention is to provide a folding stool supporting structure as aforesaid which may be manufactured more economically than similar supporting structures presently in use.

A further object of this invention is to provide a folding stool supporting structure as aforesaid which is adequately sturdy and durable.

A further object of this invention is to provide a folding stool supporting structure as aforesaid which may be collapsed easily and quickly.

A further object of this invention is to provide a folding stool, supporting structure as aforesaid which, when collapsed, is sufficiently small for easy transport, as for example, in an overcoat side pocket.

Other objects and purposes of this improvement in a folding stool supporting structure will become apparent to those familiar with this type of equipment upon reading the following specifications and upon inspection of the accompanying drawings.

In order to meet the objects and purposes heretofore set forth, I have provided a supporting structure means having a central body member to which is pivotally attached a plurality of frame members. Some of said members are pivotally fixed with respect to said body member at one of their respective ends so that their free ends may be swung above the body member for the purpose of engaging a suitable seat in any convenient manner, but more specifically as disclosed in my Patent No. 1,715,559. The free ends of the remainder of the said members are also pivotally attached to said body member at one

2

of their respective ends but are limited in the distance which they may be spread apart by stops which are an integral part of said body member. These latter frame members constitute the legs of said structure which engage the means upon which said folding stool supporting structure is to be placed.

Referring to the drawings:

Figure 1 is an oblique view of the distended supporting structure for a folding stool incorporating one embodiment of this invention.

Figure 2 is a plan view of the central body member before it is folded into its operable shape.

Figure 3 is a side elevation view of the folding stool, supporting structure in a collapsed position.

It will be observed in Figure 1 that the particular embodiment of the invention illustrated therein is comprised of a central body part 1 and frame members comprising three arms and three legs pivotally attached thereto, in pairs, at three uniformly disposed points. The three upper arms designated as 2, 3 and 4 are pivotally associated with the three legs 5, 6 and 7, respectively.

As illustrated in Figure 2, which views the central body member in the flat, said body member may be readily stamped out or otherwise cut in any conventional, convenient manner from flat durable material, preferably metal. Also as shown in Figure 2, said central body member has a center section 10 supporting three leaves 11, 12 and 13 which are integral with said center section in this particular embodiment of the invention but could quite conceivably be separate pieces suitably attached to said center section.

The said center section 10 may be triangular in shape as illustrated for convenient association with three leaves, each supporting two of the six frame members shown in Figure 1. However, it will be understood that it would be possible to design this central body part rectangularly, or otherwise polygonally, with as many edges and corresponding leaves as required by the number of frame members which are desired on the stool. For illustrative purposes, only, in this particular application the minimum condition of three upper arms and three lower arms, or legs, comprising the frame members will be described, thus resulting in the type of three leaved central body member shown in Figure 2.

The central body member 1 is broken along the line 14, 15 and 16, as shown in Figure 2, so that the leaves 11, 12 and 13 are perpendicular to and all on the same side of the center section 10. The material from which the center body mem-

ber is made is broken along the line 14, 15 and 16, as shown in Figure 2, so that the leaves 11, 12 and 13 are perpendicular to and all on the same side of the center section 10. The material from which the center body mem-

ber is fabricated will be limited only to the extent that it must be of sufficient strength to support the load for which it is designed. The openings 17, 18 and 19 are provided in the leaves 11, 12 and 13, respectively, for the reception of suitable pins, one of which is indicated at 20 in Figures 1 and 3, upon which said arms and legs are operably mounted for pivotal motion there-around. As is shown in Figures 1 and 3, the arm 2 and the leg 5 are pivotally mounted on the same pin 20, through the opening 19 in the leave 13. In this manner the arm 3 and the legs 6, as well as the arm 4 and the leg 7, are similarly mounted on suitable pins which are received through the openings 17 and 18 in the leaves 11 and 12, respectively. It may be noted in Figures 1 and 3 that the arms are swiveled adjacent to the inner surfaces of the leaves 11, 12 and 13, whereas the legs are swiveled adjacent to the outer surfaces of said leaves.

Similar corners 21, 22 and 23 of leaves 11, 12 and 13 are broken along the lines 24, 25 and 26 as indicated in Figure 2, so that the ears thereby produced will extend outwardly from the center of the body member 1 and preferably perpendicular to the respective leaves of which they are a part. Said ears thereby provide an integral stop on said leaves 11, 12 and 13 for the purpose of limiting the distance to which the legs 5, 6 and 7 may swing when the folding stool supporting structure, as shown in Figure 1, is distended for usage. Said stops, by limiting the extent to which said legs may freely swing, provided the above mentioned supporting structure with the necessary amount of stability under load.

In the central body member 1 the leaves 11, 12 and 13 do not extend the full length of the adjacent connected edges of the center 10 by which to provide a slot between each pair of adjacent parallel edges of the three leaves 11, 12 and 13, one of which slots is indicated at 30 in Figures 1 and 3, in said central body member 1. Said three slots are advantageously positioned with respect to the three arms 2, 3 and 4 so as to provide openings in which said arms may move in an upwardly direction for engagement with a suitable seat means, shown in phantom at 31. The upward movement of the arms 2, 3 and 4 will be limited by the exposed edges 32, 33 and 34 of the center section 10 of the central body member 1, as shown in Figure 2. Said arms will be held by the seat in seat supporting position, and against spreading, in any convenient manner, as that shown in the above mentioned Patent No. 1,715,559.

The supporting structure may be quickly collapsed to appear as in Figure 3 when the seat is disengaged if the arms attached to said central

body member 1 are moved pivotally downwardly. As shown in Figure 1, the arms 2, 3 and 4 will swing through a considerably larger arc for engagement with a seat means 31 than the legs 5, 6 and 7 will spread to provide a stable support, as their lower extremities engage the means upon which the stool is placed.

The arms 2, 3 and 4 and the legs 5, 6 and 7 may be made of any suitable and sufficiently sturdy material but will advantageously be made of steel. As disclosed in Figure 3, the legs 5, 6 and 7 are preferably longer than the arms 2, 3 and 4. It is, however, quite readily conceivable that the arms be longer than the legs, since the relative length of the arms and legs is essentially unimportant as far as the invention is concerned.

Although the above mentioned drawings and description apply to one particular, preferred embodiment of the invention, it is not my intention, implied or otherwise, to eliminate other variations or modifications which do not depart from the scope of the invention unless specifically stated to the contrary in the hereinafter appended claim.

25 I claim:

In a folding stool having a center member, a group of seat supporting arms extending therefrom and a group of legs extending therefrom, the improvement in said center member comprising: a polygonal central section; a depending leaf perpendicularly disposed with relation thereto extending downwardly from each side of said central section and extending along each of said sides from one end thereof to a point close to but 30 spaced from the other end; a stop near the lower edge of each of said leaves and on the edge of said leaf which connects with said one end of a side of the central section to which side a given leaf is attached; means pivotally holding said 35 seat supporting arms on said leaves within the space partially defined thereby and permitting them in one pivotal position to extend outwardly and upwardly between the said leaves and means pivotally holding the legs outside of the space defined by said center member in position with respect to said stop for limiting movement of said leg with respect to said center member at a predetermined position.

50 RALPH B. LONG.
